GB 2191377 12/1987

* cited by examiner

Primary Examiner — Cathy A MacCormac(74) *Attorney, Agent, or Firm* — Larkin Hoffman Daly & Lindgren, Ltd.; Thomas J. Oppold(57) **CLAIM**

The ornamental design of a litter pan, as shown and described.

DESCRIPTION

FIG. 1 is a front perspective view of the litter pan of the present design.

FIG. 2 is a front elevation view of the litter pan of FIG. 1.

FIG. 3 is a rear elevation view of the litter pan of FIG. 1.

FIG. 4 is a left side elevation view of the litter pan of FIG. 1.

FIG. 5 is a right side elevation view of the litter pan of FIG. 1.

FIG. 6 is a top plan view of the litter pan of FIG. 1; and,

FIG. 7 is a bottom plan view of the litter pan of FIG. 1.

The broken lines showing the structural reinforcement ribs on the bottom surface of the litter pan form no part of the claimed design.
